Des. 196,923
Patented Nov. 19, 1963

196,923

CROSS AND PLANTER COMBINATION

Gilbert Josephson, 60 Locust Ave., New Rochelle, N.Y.

Filed Feb. 15, 1963, Ser. No. 73,589

Term of patent 14 years

(Cl. D29—23)

FIG. 2

FIG. 3

FIG. 5

FIG. 6

FIG. 7

FIG. 4

FIG. 1 is a front perspective view of a cross and planter combination showing my new design;

FIG. 2 is a front elevational view thereof on smaller scale;

FIG. 3 is an elevational view as seen from the right of FIG. 2;

FIG. 4 is a rear elevational view;

FIG. 5 is a top plan view;

FIG. 6 is a bottom plan view; and

FIG. 7 is a sectional view thereof taken along the line 7-7 of FIG. 1.

I claim:

The ornamental design for a cross and planter combination, substantially as shown.
